UNITED STATES PATENT OFFICE.

AI B. SHAW, OF MEDFORD, MASSACHUSETTS, ASSIGNOR TO SHAW SPECIALTY CO. INC., OF WEST MEDFORD, MASSACHUSETTS, A CORPORATION OF MASSACHUSETTS.

STOPPER FOR HOT-WATER BOTTLES.

1,423,464.

Specification of Letters Patent. Patented July 18, 1922.

Application filed January 20, 1922. Serial No. 530,672.

To all whom it may concern:

Be it known that I, AI B. SHAW, a citizen of the United States of America, and a resident of Medford, in the county of Middlesex and State of Massachusetts, have invented certain new and useful Improvements in Stoppers for Hot-Water Bottles, of which the following is a specification.

This invention relates to stoppers for hot water bottles and has for its primary object the construction of a device of this character in which provision is made for preventing leakage between the inner end of the stopper and the usual packing ring supported thereon. Another object of the invention is the simplification of the construction of the stopper and the means thereon for supporting the usual packing ring.

The invention consists primarily in a threaded stopper having a packing ring at its inner end freely revoluble relatively to said stopper and a thin flexible washer interposed between said packing ring and the end of said stopper.

The invention further consists of a novel means for supporting the packing ring upon the stopper.

The invention further consists in a novel construction of stopper.

The invention further consists in certain novel features of construction and arrangement of parts which will be understood readily by reference to the description of the drawings and to the claims to be hereinafter given.

For the purpose of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a front elevation of a stopper embodying the principles of the present invention, said stopper being illustrated as applied to a portion of a hot water bottle which is shown in section.

Figure 2 represents a side elevation of the same. 55

Figure 3 represents a vertical section of the same, on line 3, 3 on Figure 2 and showing the bottom plate removed.

Figure 4 represents a plan of said stopper.

Figure 5 represents an inverted plan of 60 same, and

Figure 6 represents an enlarged vertical section of the lower end of said stopper.

Similar characters indicate like parts throughout the several figures of the drawings. 65

In the drawings 10 is a portion of the upper end of a hot water bottle having embedded therein a threaded socket 11 provided at the bottom with the inwardly extending flange 12. A threaded stopper 13 is adapted to be screwed into the socket 11 by means of the handle 14. In the construction herein shown, the threaded body portion of the stopper and the handle portion 70 14 thereof are formed integral and hollow. This handle portion 14 is preferably made as shown in the drawings with oppositely disposed concave portions 15, which afford a good grip for the hand when screwing the stopper into the socket 11 or removing it therefrom.

The lower end of the portion 13 of the stopper has an inwardly extending flange 16 against the under surface of which a disk 17 85 is adapted to bear. The lower end of the stopper 13 is provided with a peripheral bead 18 over which the edge 20 of the disk 17 is crimped, preferably, so that said disk 17 cannot rotate relatively to the stopper 13. 90 The disk 17 has struck therefrom a reduced cylindrical portion 21 from the end of which extends another reduced cylindrical portion 22 formed integral with the disk 17. Surrounding the reduced portion 21 and freely 95 revoluble about the axis thereof is a packing member 23.

Interposed between this packing member 23 and the disk 17 is a thin flexible metal washer 24. When the metal washer 24 and 100 packing member 23 have been positioned upon the cylindrical portion 21 and metal washer 25 is placed upon the reduced cylindrical portion 22, the end of said cylindrical portion 22 is then upset as indicated 105 at 26 to retain said washer 25 in position

and prevent the accidental displacement of said packing member 23 and metal washer 24.

The diameter of the washer 25, however, is such that if desired, the packing member 5 23 may be sprung over said washer 25 and a new packing member 23 substituted therefor. The washer 24 is very thin and flexible and as a consequence, the packing member 23 will force the washer 24 into contact with 10 the under face of the disk 17 and cause it to conform to any irregularities in the face thereof. This will effectually prevent any liquid in the bottle from leaking by the inner wall of the packing member 23 and outwardly between the threaded portion 13 of 15 the stopper and its enclosing socket 11. The washer 25 is positioned on the reduced end 22 sufficiently far from the disk 17 as to permit the free rotation of the packing 20 member 23 about the cylindrical reduced portion 21. By means of this construction of the disk 17, a simple means is provided for retaining the washer 24 and packing member 23 upon the stopper without the 25 necessity of using rivets or other securing members.

When the stopper is being inserted into the socket 11, the packing member 23 will rotate therewith until its under face comes 30 into contact with the flange 12 upon the socket 11, and then the frictional contact between the two will be sufficient to prevent further rotation of the packing member 23, while the stopper is being further rotated to 35 compress the packing member 23 against the flange 12.

Heretofore in stoppers of this character, the packing member 23 is usually rotated with the stopper and soon becomes worn and 40 useless if it is rotated while in contact with the flange 12. When the packing member 23 has been compressed against the flange 12 by the continued rotation of the stopper, all leakage between said flange and the 45 packing member is effectually prevented.

The thin metal washer interposed between the packing member 23 and the disk 17 will rotate with the packing member 23 thereby causing the upper face of said metal washer 50 24 to rotate in contact with the disk 17. By this construction the rubbing of the upper surface of the packing member 23 against a metal surface is prevented and consequently there will be no wear upon said packing member as would be the case if said packing member rotated in contact with a 55 fixed metal surface.

If desired, two packing members 23 may be used upon the reduced end 21, one of 60 which bears against the under face of the disk 17 and the other bears against the washer 22. In such a construction two thin metal washers 24 would be interposed between the packing members 23 so that when the lower 65 packing member 23 rotated about the cylind-

rical portion 21, one of the metal washers 24 would rotate therewith in contact with the other washer 24 which would remain stationary in contact with the upper packing member.

In the stoppers now in general use, the packing member is secured firmly to the stopper and when the stopper is rotated and the packing member is in contact with its seat on the flange 12, the rubbing contact is liable to injure and soon destroy the packing member. As there is no ready means of renewing this packing member, the entire stopper is useless and an entirely new stopper must be substituted. In the present construction, should the packing member become sufficiently damaged to make it useless, the damaged packing member may be quickly removed and a new one substituted therefor.

This simple construction of stopper is more effectual in use as it makes hot water bottles absolutely non-leakable at its filling point and the life of the stopper itself is greatly prolonged. Moreover it provides a means whereby a new packing member may be placed quickly upon the stopper, thus making it unnecessary to throw away all of the stopper. The entire device is of very simple construction and the cost of the manufacture of same is reduced to a minimum.

It is believed that the operation and many advantages of the invention will be readily understood without further description.

Having thus described my invention, I 100 claim:

1. A threaded bottle stopper having a bottom plate provided with a central flanged projection; a packing member freely revolvable about said flanged projection; and a 105 metal washer between said packing member and bottom plate.

2. A threaded bottle stopper having a bottom plate provided with a central flanged projection; a packing member freely revolvable about said flanged projection; and a thin metal washer between said packing member and bottom plate adapted to conform to the face of said bottom plate.

3. A threaded bottle stopper having a 115 reduced cylindrical portion at its inner end; a packing member freely revolvable about said reduced end; a metal washer between said packing member and the body portion of the stopper; a flanged stud projecting from and formed integral with said reduced end; and a washer on said reduced end for retaining said packing member on said reduced end.

4. A threaded bottle stopper having a 125 reduced cylindrical portion at its inner end; a packing member freely revolvable on said reduced end; a metal washer between said packing member and the body portion of the stopper; a flanged stud projecting from 130

said reduced end; and a metal washer between the flange of said flanged end and said packing member.

5. A threaded bottle stopper formed with an open end having an outwardly extending flange; a bottom plate the edge of which is crimped over said flange and thereby secured thereto; a cylindrical projection on said bottom plate; a packing member freely revoluble about said projection; a thin flexible washer between said plate and packing member; and means for retaining said packing member and washer in said projection. 10

6. A threaded bottle stopper formed with an open end having an outwardly extending

flange; a bottom plate the edge of which is crimped over said flange and thereby secured thereto; a cylindrical projection on said bottom plate; a packing member freely revoluble about said projection; a thin flexible washer between said plate and packing member; and means for retaining said packing member and washer on said projection. 20

Signed by me at 746 Old South Bldg., Boston, Mass. this 19th day of January, 1922. 25
